C. S. BOCK

CLOSURE FASTENING BOLT

Filed Feb. 7, 1924

Witness: *P. Burkhardt*

UNITED STATES PATENT OFFICE.

CHARLES S. BOCK, OF CHICAGO, ILLINOIS, ASSIGNOR TO ANDREW HOFFMAN MFG. CO., OF CHICAGO, ILLINOIS, A CORPORATION OF ILLINOIS.

CLOSURE-FASTENING BOLT.

Application filed February 7, 1924. Serial No. 691,104.

The invention relates to closure-fastening bolts, such as are particularly applicable to casement windows, doors, and like structures.

- 5 The principal object of the invention is to provide a closure-fastening bolt which may be easily manipulated to effect a stable connection of the closure with both the lintel and sill of the associated closure frame.
- 10 Another important object is to provide such a bolt which is adapted to function in the dual capacity of a bolt and hinge in such articulated closures as double casement windows, folding doors, and like structures,
- 15 wherein the connection of the closure with both the lintel and sill of the associated frame may be quite advantageously located in alignment with the articulated portion of the closure.
- 20 Another object is to provide such a bolt which is of a pleasing though inconspicuous appearance, and which is possessed of a simple yet durable construction susceptible of very economical production.
- 25 While the foregoing statements are indicative in a general way of the nature of the invention, other objects and advantages not specifically referred to in this disclosure will be obvious upon a full understand-
- 30 ing of the construction and operation of the both as set forth in the following description and accompanying drawings, wherein is presented a preferred embodiment of the invention. It will be understood, however,
- 35 that such particular embodiment is chosen primarily for the purpose of exemplification, and is not intended to restrict in any way the spirit of the invention or to limit unnecessarily the scope of the appended
- 40 claims.

In the drawings:—

Fig. 1 is a fragmentary inside view of a double casement window which is provided with the bolt of the invention;

45 Fig. 2 is a horizontal section on the line 2—2 of Fig. 1, showing the bolt in locked position;

50 Fig. 3 is a horizontal section corresponding to Fig. 2, showing the bolt in the unlocked position;

Fig. 4 is a vertical section on the line 4—4 of Fig. 1;

55 Fig. 5 is a horizontal section corresponding to Fig. 2, showing a slightly modified form of the invention;

Fig. 6 is a vertical section on the line 6—6 of Fig. 5, and

Fig. 7 is an inside view of the upper portion of that form of the bolt illustrated in Figs. 5 and 6.

The closure-fastening bolt of the invention includes a rod 10, a number of rod-journailling brackets 11 secured to the associated closure 12, a manipulating handle 13 secured to an intermediate portion of the rod 10, two latching members 14 and 15 secured to the upper and lower ends respectively of the rod 10 with their bearing surfaces tangential to a curve described about the axis of the rod, and two striker-plates 16 and 17 secured to the lintel and sill respectively of the associated frame 18 with their bearing surfaces in the line of thrust of the rod 10 when the latter is in a locked position.

The closure 12, to which the closure-fastening bolt is applicable, may be in any one of many different forms, but in the present disclosure is exemplified in the form of a double casement window having two sash portions 19 and 20 which are pivotally connected at their abutting margins to each other and at their separated margins with two members slidably mounted in the lintel 21 and sill 22 of the frame 18. Such a window is opened or closed by moving the hinged margins of the sash portions away from or into the plane of the frame. The closure-fastening bolt, when applied to such a window, may function in the dual capacity of a bolt and hinge by employment of the rod 10 as the pivot between the sash portions 19 and 20 and employment of the brackets 11 as the lapped hinge butts for the pivot between the sash portions.

The rod 10 which is preferably of circular cross-section throughout its length, extends vertically along the junction of the sash portions 19 and 20 to points adjacent the lintel 20 and sill 22 of the frame. The brackets 11 are arranged in pairs like hinge leaves and are secured at opposite sides of the rod 10 to the margins of the sash portions 19 and 20. The handle 13 is secured to the rod 10 at about the middle of the same, and is arranged parallel to the plane of the frame when the rod is in the locked position shown in Fig. 2 and perpendicular to the plane of the frame when the rod is in the unlocked position shown in Fig. 3. The

2
latching members 14 and 15 are secured to the ends of the rod 10 and have flanges 23 which extend beyond the ends of the rod to provide flat bearing surfaces 24 tangential to a curve described about the axis of the rod. The striker-plates 16 and 17 are secured to the lintel 21 and sill 22 of the frame, and have horizontal flanges 25 which extend inwardly from the plane of the window and are curved, as shown in Fig. 2, to provide curved bearing surfaces 26 on their edges for coaction with the bearing surfaces 24 of the latching members 14 and 15.

The disposition of the striker-plates 16 and 17 on the lintel 21 and sill 22 of the frame is such that, when the bolt is in the unlocked position and the sash portions 19 and 20 are being moved by the handle 13 away from or into the plane of the window frame, the striker-plates will not interfere with the latching members 14 and 15, and that, when the sash portions are in their closed position and the bolt is turned by the handle into the locked position, the bearing surfaces 24 of the latching members will ride about the curved bearing surfaces 26 of the striker-plates and will, by such coaction, draw the sash portions into a tightly closed position as the bearing surfaces 24 of the latching members assume a position in parallelism with the plane of the window. The bearing surfaces 26 of the striker-plates curve inwardly at 27 away from the bearing surfaces 24 of the latching members in order to avoid engagement between the bearing surfaces 24 and 26 at points other than those tangential to curves described about the axis of the rod with radii corresponding to the offset of the bearing surfaces 24. Such supplemental curvature of the bearing surfaces overcomes any tendency which the rod 10 might otherwise have to shift into a partially unlocked position under continued jarring of the sash portions. The disposition of the bearing surfaces 24 tangential to a curve described about the axis of the rod 10 results in a stable engagement of the latching members with the striker-plates, since any attempt to move the sashes from their closed position acts through the pivotal axis of the rod against the bearing surfaces 24 in a direction normal to the same at their point of engagement with the bearing surfaces 26 of the striker-plates in the line of thrust of the rod.

In Figs. 5, 6 and 7 is shown a slightly modified form of the invention wherein the upper latching member 14 is provided with a horizontal flange 28 which is upwardly tipped at its forward end. The flange 28 is intended to ride onto the flange 25 of the upper striker-plate 16 as the sash portions assume their closed position, and serves to support the sash portions medially when the same are in either their closed or locked posi-

tion. This arrangement is particularly of advantage in wooden sash structures where in warping or settling might occur.

While the bolt of the invention is illustrated in the present disclosure in association with a double casement window and in such association functions in the dual capacity of a bolt and hinge, it will be appreciated that the invention is applicable to all forms of closures.

I claim:—

1. In a closure-fastening device, a pivotally mounted latching member adapted for connection with an associated closure and provided with a bearing surface which faces toward the pivotal axis of the member and is tangential to a curve described about such axis, and a striker adapted for connection with an associated closure frame and provided with a bearing surface which faces away from the direction in which the closure is openable and is adapted for engagement with the bearing surface of the latching member in the line of thrust of the latter when in a locked position.

2. In a closure-fastening bolt, a rod, a rod-journalling bracket adapted for attachment to an associated closure, a handle secured to the rod for turning the same into a locked or unlocked position, a latching member associated with the rod and provided with a bearing surface which faces toward the pivotal axis of the rod and is tangential to a curve described about such axis, and a striker adapted for attachment to an associated closure frame and provided with a bearing surface which faces away from the direction in which the closure is openable and is adapted for engagement with the bearing surface of the latching member in the line of thrust of the rod when the latter is in a locked position.

3. In a closure-fastening bolt, a rod, a number of rod-journalling brackets adapted for attachment to an associated closure, a handle secured to a medial portion of the rod for turning the same into a locked or unlocked position, two latching members secured to the upper and lower ends of the rod and provided beyond such ends with bearing surfaces which face toward the pivotal axis of the rod and are tangential to curves described about such axis, and two striker-plates adapted for attachment to the lintel and sill of an associated closure frame and provided with curved bearing surfaces which face away from the direction in which the closure is movable and are adapted for engagement with the bearing surfaces of the latching members in the line of thrust of the rod when the latter is in a locked position.

4. In a closure-fastening bolt, a rod adapted to function as a movable pivot between two articulated sash portions, a number of rod-journalling brackets adapted for attach-

ment to the sash portions adjacent the pivoted margins of the same, a handle secured to a medial portion of the rod for moving the sash portions into a closed or open position 5 and for turning the rod into a locked or unlocked position, two latching members secured to the upper and lower ends of the rod and provided with bearing surfaces which are tangential to curves described about the 10 axis of the rod, and two striker-plates adapted for attachment to an associated closure frame and provided with curved bearing surfaces which are adapted for engagement with the bearing surfaces of the latching 15 members in the line of thrust of the rod when the latter is in a locked position.

5. In a closure-fastening bolt, a rod, a rod-journalling bracket adapted for attachment to an associated closure, a handle secured to the rod for turning the same into a 20 locked or unlocked position, a latching member secured to the upper end of the rod and provided with a vertical flange having a bearing surface which is tangential to a 25 curve described about the axis of the rod and

with an overhanging flange having a bearing surface which is substantially horizontal, and a striker-plate adapted for attachment to an associated closure frame and provided with a horizontal flange having a curved bearing 20 surface on its edge which is adapted for engagement with the bearing surface of the latching member in the line of thrust of the rod when the latter is in a locked position and with a top bearing surface onto which 35 the under bearing surface of the latching member is adapted to ride.

6. In a device of the character described, the combination with an open frame, and two articulated sash portions which are movable into or out of a plane of the frame, of a hinging rod to which the sash portions are connected for articulation, and means acting through the rod between the sash portions and the frame to hold the sash portions 40 against movement out of the plane of the frame.

In testimony whereof I have hereunto signed my name.

CHARLES S. BOCK.
